UNITED STATES PATENT OFFICE.

RAY SETH WILBUR, OF LYNDHURST, NEW JERSEY, ASSIGNOR TO WESTERN ELECTRIC COMPANY, INCORPORATED, OF NEW YORK, N. Y., A CORPORATION OF NEW YORK.

TELEPHONE-REPEATER MONITORING SYSTEM.

Application filed June 18, 1921. Serial No. 478,494.

To all whom it may concern:

Be it known that I, RAY S. WILBUR, a citizen of the United States, residing at Lyndhurst, in the county of Bergen, State of New Jersey, have invented certain new and useful Improvements in Telephone-Repeater Monitoring Systems, of which the following is a full, clear, concise, and exact description.

The present invention relates to monitoring circuits for telephone repeating stations and like purposes.

An object of the invention is to provide a simplified type of monitoring circuit suitable for listening in on transmissions passing through a repeating station, without disturbing the normal operation of the repeater. A further object is to provide a combined monitoring circuit and communication channel, for example over either line section coming into a two-way repeating station, and particularly between two separated repeating stations, over which channel an attendant at a distant station may be called into conversation from another station on the line.

For this purpose the system of the invention provides preferably at each repeating station on a line one or more sources of suitable ringing current, talking and listening sets and simplified switching arrangements, by which listening, talking and signalling can be carried on over either or both sections of the line with facility and despatch.

A feature of the invention is the simple and economical way in which the monitoring and signalling apparatus is coupled to one or the several line circuits. It is desirable to associate monitoring equipment with the output circuit as then a satisfactory volume of monitoring current may be secured without appreciably reducing the normal transmission. Heretofore listening-in or monitoring sets designed for use with repeater circuits in which the output transformer is made the balanced coil, have required extra repeating coils inserted in the line sections. These are expensive to build and have the disadvantage that they must be

balanced in the same way that the other elements of a line must be balanced. Furthermore the primary windings of such coils are always in the line whether the monitoring sets are being used or not, with the necessary resulting transmission loss and complications.

The present invention, however, employs simply a few turns of wire on the usual balanced repeater coil itself to serve as an extra winding for the monitoring apparatus. This winding can be applied readily during the manufacture of the coil, and in fact it has been found to involve such small expense that it has proved practical to incorporate such a winding in making repeater coils even where the chance of ever using the winding for monitoring is quite uncertain, so great is the convenience and the saving in time and labor by having the winding in readiness in those cases where it will subsequently be needed. As will be pointed out this winding is often valuable for shielding purposes whether it is used for monitoring or not. Such an auxiliary winding may equally well be employed where the output coil is not the balanced coil but is used in a bridge. In that case it saves the use of an auxiliary coil to avoid metallic connection between the repeater circuit and the monitoring set.

For a more complete disclosure of the invention and its mode of operation, a description of a typical repeater circuit embodying the invention will now be given, reference being had to the accompanying drawing in which Fig. 1 shows a schematic circuit arrangement of the repeating station for one line; Fig. 2 shows an alternative manner of associating the monitoring winding with the line; and Fig. 3 shows a different manner of applying the monitoring winding.

The line is shown as divided into the usual east-west sections LE and LW associated with each other through two one-way repeating paths RE and RW. To prevent circulation of energy around the repeating paths the line sections are provided with the usual

balancing circuits BE and BW and with the balanced repeating coils comprising the series line windings 1, 2, 3 and 4 associated with the repeater output coils 5, 6. All of 5 this apparatus is well known in the art and it is clear that with proper line balances transmissions may, pass from section LE through the repeater RW and on to the line LW without finding their way into the in- 10 put of the repeater RE and similarly transmissions may pass in the opposite direction through repeater RE.

According to the form of the invention shown in Fig. 1 an extra winding comprising sections 7 and 8 is applied to the balanced repeating coil to serve for monitoring and signalling. In construction this winding may comprise a relatively small number of turns of fine wire and may be situated 15 next to the core or between the primary and secondary windings or outside of the primary and secondary windings. It thus occupies little space and its presence does not therefore interfere with the efficient design 20 of the output transformer for its usual and normal function.

The terminals of the windings 7, 8 are brought out to the respective jacks JE and JW to connect the monitoring apparatus 30 with the line. The plugs 9 and 10 will be inserted into their respective jacks and for normal listening over both lines the key K will be thrown to its upper position where it may if desired be locked thus holding its 35 springs in their separated positions. A circuit then exists including the monitoring windings 7 and 8 of line LW, spring of jack JW, tip of plug 9, contact 11 now closed, contacts 12 and 13 normally closed, the re- 40 sistance R, attendant's receiver 20, contacts 14 and 15 normally closed, contact 16 of key K, sleeve contacts of plug 10 and jack JE, windings 7 and 8 of line LE, spring and tip of plug 10, contact 17, sleeve contacts of 45 plug 9 and jack JW to the opposite terminal of monitoring windings 7 and 8 of line LW. With this circuit established the attendant can listen to transmissions passing over either line section. The windings 7 and 8 50 are related to the line windings 1, 2, 3, and 4 in the same manner as are the repeater output windings 5 and 6, and the windings 7 and 8 serve, therefore, to receive currents in- 55 coming over the line, or to transmit current over the line, or to receive currents from the repeater output windings 5 and 6. Current impressed on the windings 7 and 8 from the monitoring circuits will not, however, af- 60 fect the input of the repeater, since they are applied to the line side and line-balance side of the input terminal in the same manner as are the repeater output coils 5 and 6. With the circuit established as above traced, 65 therefore, if the repeaters are operative, the attendant hears signals due to received un-

amplified current over one line section and the same current after it is passed through a repeater and therefore become amplified, since the two monitoring coils are connected in series.

The object of the resistance R is to make the impedance of the receiver circuit, as used in the monitoring connection, so high that only a small fraction of the outgoing transmission is drawn off into the monitoring receiver through the windings 7-8. If only one hundredth of the outgoing energy is drawn off through this circuit the volume of monitoring transmission will still be as great as that heard on the average by the subscriber at the distant end. When this is done the impedance of the monitoring circuit is relatively high as compared to that of windings 7-8 and the connection of the monitoring circuit changes conditions only slightly from that of leaving this winding open circuited. On the other hand the impedance of the talking sets should be designed to match that of the monitoring connection to afford an efficient communication channel for the repeater attendants.

If the attendant desires to talk over both line sections at once he leaves the key K in its up position and throws the double throw key DK to the right in the drawing. This separates the key springs opening contacts 13 and 14 and closes contacts 21 and 22. This alters the circuit previously traced by establishing a path from contact 11 through contact 21, secondary of microphone repeating coil 23, contact 22, contact 16 and from thereon as previously traced. Speech currents set up by the microphone T therefore pass to both line sections but do not affect the input of either repeater as described. When the key DK was thrown as described the receiver 20 was cut off at contacts 13 and 14 but is connected across one half of the secondary of repeating coil 23 thereby providing side tone in the receiver and furnishing an efficient circuit for receiving over either line section.

If it is desired to transmit ringing current over both line sections at the same time, the key DK is thrown to the left in the drawing separating the left hand springs and opening the contacts 12 and 15 of the normal listening circuit and closing contacts 24 and 25 leading to a source of suitable ringing current RC. From contacts 24 and 25 the circuit is as previously traced to the monitoring windings of the two line sections in series. During ringing the attendant's transmitter and receiver are disconnected at contacts of key DK.

If it is desired to listen, talk or ring over line section LE the key K is thrown to the down position to open its springs and the key KE is thrown to the up or closed position. A circuit then exists from the jack

JE and plug 10 to the key contacts 26, 27 and thence to the common leads 28 and 29 to the double throw key DK and depending upon the position of this key the circuit may 5 be extended to the receiver 20 or to the repeating coil 23 or to the ringing source RC.

In similar manner if the key KW is closed and keys K and KE are opened a circuit is established from the monitoring coil of 10 the line LW, jack JW, plug 9 through the key contacts 30 and 31 to the common leads 28, 29, for connecting any of the monitoring apparatus desired to the line section LW.

In Fig. 2 is shown a method of positioning 15 and utilizing the monitoring windings 7 and 8 which often proves convenient. The windings 7 and 8 are positioned between the line windings 1, 2, 3, and 4 and the repeater output windings 5 and 6 and the mid-point of 20 the windings 7 and 8 is connected directly to ground. This provides an effective electrostatic shield and acts very much as if a grounded metallic sheath were inserted between the primary and secondary windings 25 of the balanced repeating coil. If both monitoring windings are arranged in this manner a tendency of the repeater to sing due to electrostatic differences of potentials around the repeater circuit is opposed.

In each of the Figures 1 and 2 the output 30 of the repeater is associated with the outgoing line through the inductively related windings of the balanced repeating coil. In some cases the arrangement is to connect the 35 output circuit of the repeater to the bridged circuit of the repeating coil as shown in Fig. 3, where the output of repeater RE is connected through transformer 40, 41 to the bridged circuit 42. In such a case the monitoring winding may be applied to the output transformer 40, 41, the monitoring winding being indicated at 43.

It will be understood that the apparatus 45 shown at the monitoring station and the keys for controlling the various connections are 50 illustrative of only one of many possible arrangements and that the principal object of the invention once having been shown it will be obvious that these circuit arrangements may be widely changed to meet varying conditions without departing from the spirit of the invention the scope of which is defined in the appended claims.

What is claimed is:

1. In a monitoring and signaling system 55 for a telephone repeater station, said repeater station having line sections interconnected through oppositely directed repeaters, a balanced repeater coil for each of the 60 interconnected line sections, and monitoring and signaling coils each comprising an extra winding inductively related to the line windings of said repeating coil but out of conductive relation to the line circuit, said system comprising telephone talking and sig-

naling sets and circuit arrangements for connecting said sets to the monitoring coil of one line section or of each of a plurality of line sections for signaling or talking over said line section or sections. 70

2. A telephone transmission line containing 75 a repeating station equipped with balanced repeating coils, and being provided with circuit arrangements for utilizing said coils for monitoring transmissions over said line or for talking or signaling over one or both line sections terminating at said repeating station.

3. A monitoring and talking circuit for 80 telephone repeater stations employing a balanced repeating coil in the line, said circuit comprising an extra winding inductively related to the line winding of said repeating coil but out of conductive relation to the circuit, a receiver, a circuit of such high impedance as to have negligible reaction on the normal repeater action for closing said extra winding through said receiver, a talking set for enabling the monitoring operator to communicate over the line through said extra winding, said talking set being proportioned to such an impedance as to give efficient transmission to the connected transmission lines. 85

4. In a repeater circuit including balanced 90 repeater output windings mounted on a common core, a supervisory winding mounted on said core and in inductive relation to said repeater output windings and circuit arrangements for utilizing said coil for talking 95 and listening purposes. 100

5. In a repeating arrangement for a line, 105 a balanced transformer winding including in the line circuit, a repeater having its output circuit inductively coupled to the balanced transformer winding, an auxiliary winding inductively associated with said transformer and supervisory apparatus connected in circuit with said auxiliary winding. 110

6. A line, a balancing circuit therefore, transformer windings in said line and balancing circuit, a repeater input circuit connected to the mid-points of said windings, a repeater output circuit inductively related 115 to said windings, an auxiliary winding inductively associated with said windings and supervisory apparatus connected in circuit with said auxiliary winding.

7. A line, a balancing circuit therefore, transformer windings in said line and balancing circuit, a repeater input circuit connected to the mid-points of said windings, a repeater output circuit inductively related 120 to said windings, and an auxiliary winding inductively associated with said windings and connected in circuit with supervisory apparatus, said auxiliary winding being balanced, whereby energy from said supervisory apparatus divides substantially equally 125 130

between said line and said balancing circuit.

8. A monitoring and signaling circuit for telephone repeater stations employing a balanced repeating coil comprising a monitoring and signaling winding inductively related to the line windings of said repeating coil but out of conductive relation to the line

circuit, and means for utilizing said monitoring and signaling winding for signaling and talking purposes.

In witness whereof, I hereunto subscribe my name this 15th day of June A. D., 1921.

RAY SETH WILBUR.
